UNITED STATES PATENT OFFICE.

FREDERIC H. MOORE, OF BOSTON, MASSACHUSETTS.

COMBINED DUST-EXCLUDER AND WINDOW-FASTENER.

SPECIFICATION forming part of Letters Patent No. 292,839, dated February 5, 1884.

Application filed October 6, 1883. (No model.)

To all whom it may concern:

Be it known that I, FREDERIC H. MOORE, a citizen of the United States, residing at Boston, in the county of Suffolk and State of Massachusetts, have invented a new and useful Improvement in Combined Dust-Excluders and Window-Sash Fasteners, of which the following is a specification.

The object of my invention is to prevent dust from coming into the rooms of a house between the "meeting-rails" of the upper and lower sashes of the windows, and at the same time to provide a simple and efficient fastening for the windows.

The invention consists of one or more thin pieces of metal, wood, or other suitable material hinged and attached to the top of the meeting-rail of lower or inner sash of the window in such a manner that the loose fold or flap may fall down and cover the joint between the meeting-rails and a portion of the meeting-rail of the upper or outer sash of the window, and by means of suitable fastenings, staples, or hooks, &c., can be securely locked, and also easily turned up to allow the sashes to pass each other in opening the window.

Referring to the accompanying drawings, Figure 1 represents my invention as applied to the meeting-rails of the upper and lower sashes of a window. Fig. 2 is a vertical section through the meeting-rails with the flap closed. Fig. 3 is a similar section, showing the flap as open. Fig. 4 is a view similar to Fig. 1, the flap being of metal and differently hinged. Fig. 5 is a vertical section of the same.

A A represent the window-frame, and B B and E the side and center bars of the upper or inner sash in section. C C' are the glass panes. D is the meeting-rail of the lower or inner sash, and D' the meeting-rail of the upper or outer sash.

In Fig. 1, G represents a thin narrow strip of wood or other suitable material secured to the top of the meeting-rail of the lower or inner sash, D. To the strip G is attached, by means of hinges H, a similar, but somewhat

wider, strip, F, forming a flap which covers the joint between the two meeting-rails, and when the said flap is opened, as shown in Fig. 3, it is thrown back sufficiently far to allow the meeting-rails of the sashes to pass each other.

I I are flat hooks, which are pivoted to the stationary strip G and catch in pins on the flap F, thus securely fastening the flap over the joint, drawing the two sashes together, and at the same time forming a secure fastening to the window and preventing any tampering with the fastenings from the outside. When the strips are made of metal, the inner edges of each are turned to form hinges, and connected together, as shown in Figs. 4 and 5.

The under side of the flap may have a lining of cloth, rubber, or other suitable material, if desirable.

I do not confine myself to the use of either metal or wood alone, as the protector may be made of a combination of both.

I am aware that a "sliding plate" has been arranged on the upper edge of the lower sash, and also that "guard-strips" have been used on window-sashes and window-screens. These I do not claim; but

What I claim as my invention is—

1. The combination of the strip G, secured to the top of the meeting-rail of the lower sash, D, of a window, with the hinged flap F, as shown and described.

2. The combination, with the meeting-rails D D' in a window-sash, of a hinged cover, F, and hooks I I, the latter pivoted to the strip G, and engaging with pins on the hinged flap F, substantially as and for the purpose set forth.

In testimony whereof I have signed my name to this specification in the presence of two subscribing witnesses.

FREDERIC H. MOORE.
